UNITED STATES PATENT OFFICE.

JAMES M. PEERSON, OF FLORENCE, ALABAMA.

TRAMPER.

Application filed March 1, 1919. Serial No. 280,188.

To all whom it may concern:

Be it known that I, JAMES M. PEERSON, a citizen of the United States of America, residing at Florence, in the county of 5 Lauderdale and State of Alabama, have invented certain new and useful Improvements in Trampers, of which the following is a specification.

This invention relates to improvements in 10 cotton trampers, and has for its principal object to design a continually driven power mechanism capable of acting through toggle mechanism to intermittently raise and lower the platen or press head so as to 15 compress the cotton into the baling box as it is fed to the trumper by any suitable mechanism, the feeding taking place when the platen is raised out of the press box, in which position the toggle arms have their 20 smallest angular divergence.

My object in utilizing the toggle mechanism as a motion transmission means between the continuously driving power means and the platen, is that it is peculiarly 25 suited to the ends of the trumper in that its power is increased gradually and in proportion as the load comes on it and its movement is accelerated as it is lifted from the press box and slowed up as it reaches 30 the point of maximum compression. A further object is to so dispose the toggles as to obtain the maximum stroke of the platen for a given length of stroke of the toggle operating crank arms, and to this end the 35 platen engaging ends of the toggles are offset so that they diverge towards each end of the platen, thereby spacing their platen engaging ends materially farther from the press center than their other ends. The extent 40 to which the point of connection of the toggles to the platen is offset determines the increase of stroke obtained.

A further object is to so connect the toggles to their operating parts as to cause 45 the toggles to break across the center of the press, thereby making possible an extremely deep stroke into the press box without danger of striking its walls.

The advantage of having a continuous 50 drive is that the entire power mechanism is simplified and reduced in cost and it further enables me to dispense with fluid pressure (air, steam or hydraulic) cylinders and thus any possibility of wetting the cotton 55 during the tramping mechanism is eliminated. The continuously driven trumper

also requires much less power for operation than the intermittently operated trampers and requires no trumper operator.

My invention also comprises the novel 60 details of construction and arrangements of parts, which in their preferred embodiments only are illustrated in the accompanying drawings which form a part of this specification, and in which:—

Fig. 1 illustrates a side elevation of my 65 improved trumper mechanism with an ordinary double revolving press box shown in outline.

Fig. 2 is a top plan view of Fig. 1; and 70

Fig. 3 is an end elevation of the platen showing the preferred manner of connecting the lower toggle links thereto.

Similar reference numerals refer to similar parts throughout the drawings.

As illustrated, 1 and 2 represent the baling 75 boxes of a revolving press of any standard construction having overhead timbers 3 which are spaced by and made fast between the central collars 4 on the vertical shaft 5 about which the double press box turns. Above the press box and parallel with the timbers 3 is provided an overhead horizontal timber 6 which at its right hand end is made fast between spaced vertical 80 timbers 7 secured at their lower ends to the timbers 3. At its left hand the timber 6 is supported by a rod or column 8 between collars 9 thereon, the rod 8 being made fast to the flooring or foundation for the 85 press. Between the uprights 7 I mount a driven sprocket or equivalent press transmitting wheel or pulley 10 which is keyed on a shaft 11 which turns in bearings 12^a mounted on the uprights 7. The main transmission gear 10 is driven by a pinion 12 fast on a power shaft 13 driven from any suitable 90 source of power and mounted at its out-board end in bearings (not shown) which are sufficiently loose to permit the gear 100 carrying end of the shaft to move with the bearing 14 which is free to have a limited swing towards and from the gear wheel 10 by reason of its suspension on a hanger bar 14^b which is pivotally supported by an overhead transverse bolt 14^c inserted horizontally through the overhead timber 6. A handle 14^a pivoted on the timber 3 and provided with any suitable latching means 110 will serve to throw the pinion 12 into or out of mesh with the gear wheel 10.

The ends of the shaft 11 project beyond

the uprights 7 and at the opposite ends of the shaft are keyed the crank arms 15 and 16 disposed in opposite directions, i. e., 180° apart. The crank arm 15 is connected by a 5 link 17 with the lower end of a toggle arm 18, which in turn is connected by a link 19 to the platen 20 at or near the center of one end thereof. The other crank arm 16 is connected by a link 21 to the lower 10 end of the toggle arm 22 which in turn is connected by a link 23 to the other end of the platen. The toggle arms 18 and 22 are mounted to turn on the overhung ends of a shaft 24 rigidly mounted in common 15 bearing 25 on the timber 6. The shaft 24 is in a transverse center plane through the press box while the lower ends of the toggles are materially offset relatively to said plane.

The lower ends of the arms 18 and 22 are 20 preferably provided with yokes 26 spaced enough to clear each other as the arms pass in the opening and closing movements of the toggles. The upper ends of the lower toggle arms 19 and 23 are received in and pivotally 25 connected to these yokes. In order to better distribute the thrust from the slightly offset toggles to the platen so as to avoid any tendency to cook the latter, I preferably attach to the longitudinal top timbers of the 30 platen 27 upstanding bearing brackets 28. The brackets 28 of each pair disposed at each end of the platen are spaced to correspond with the spacing of the top toggle arms 18 and 22 and in each pair of brackets I rigidly 35 mount a shaft 29. The lower toggle arms 19 and 23 are pivotally connected to their respective shafts 29 but being spaced, more closely than the upper toggle arms, will engage these shafts not far from and on opposite 40 sides of their centers and the thrust transmitted through the shafts will be substantially evenly distributed crosswise of the platen. Should it be deemed necessary to 45 guide the platen in its travel above the press box any suitable type of guide may be employed, that shown being guide rods 30 mounted on the platen in position to clear the toggle arms and adapted to work through guide bearings 31 in the overhead 50 timber 6.

In operation, when cotton is ready to be fed from the condenser to the press box below the platen by any suitable feed mechanism (not shown) the gear 12 is moved into 55 mesh with the gear 10 and the trumper starts. As the wheel 10 turns the cranks 15 and 16 produce a reverse travel of the links 17 and 21 and these being connected at the knuckle of the toggles formed by the members 18, 19 and 22, 23, serve to produce a 60 gradual and simultaneous opening and closing of the two toggles with a resultant raising and lowering of the platen. The trumper is continuously driven until the bale is completed, it being noted that the toggles are 65

adapted to assume a position of maximum power transmission efficiency as the platen reaches the bottom of its travel.

To get the maximum travel for the platen without interference with the frame or boxes 70 I arrange the toggles with their lower ends spaced farther apart than their upper ends and so connect them to the crank wheel that their knuckle joints move past the transverse central vertical plane through the 75 platen as they lift the latter to its highest or full open position. This permits the toggle joints to break and their elements assume sharp relative angularity without engagement with the box walls or frame. Moreover the lower toggle ends being offset from the platen center relatively to their upper ends, they will lift the platen higher for a given length of stroke of their operation.

This invention is adapted without departure 80 from the essential principles of its construction to be adapted to compress various classes of material other than cotton, and it may be variously modified within the scope of the appended claims.

Having thus described my invention, what I claim as new and desire to secure by Letters Patent, is:—

1. In a trumper mechanism, the combination with a baling box and a platen movable 95 thereinto, of mechanism for reciprocating the platen comprising reversely moving toggles, and a common continuously driven power element for operating the toggles, the toggles being so attached to the platen as to 100 diverge towards the platen when the links of each toggle are in alignment.

2. In a trumper mechanism, the combination with a baling box and a platen movable 105 thereinto, of mechanism for reciprocating the platen comprising reversely moving toggles, a common continuously driven power element for operating the toggles, means to interrupt the driving of said power means, the toggle at one end being 110 connected to the platen near its ends, and overhead bearings for the other end of the toggles which bring said latter ends materially closer than their platen ends.

3. In a trumper, the combination with a 115 baling box and a platen movable thereinto to compress the material under treatment, of mechanism for operating the platen comprising an overhead bearing disposed substantially over the center of the platen, 120 toggle arms swung therefrom, links connecting the toggle arms with the platen near its ends, a power driven shaft having oppositely disposed cranks thereon, and links connecting said cranks to the knuckle joints of 125 the toggles for opening and closing the latter to reciprocate the platen.

4. In a trumper, the combination with a 130 baling press and a platen movable thereinto, of a link pivotally connected near

each end of the platen, an overhead shaft disposed transversely above the center of the press box, a pair of toggle arms pivotally mounted on said shaft and each connected 5 to one of said links, a double crank shaft having the crank elements thereof spaced 180° , and arms connecting each crank to the knuckle joint of its respective toggle, said parts being arranged to cause the toggle 10 joints in breaking to move across the transverse center of the platen.

5. In a trumper mechanism, a press box, a platen movable thereinto, a shaft parallel with the transverse center of the platen, two

pairs of toggle links hung from said shaft 15 and connected to opposite ends of the platen, and power driven crank mechanism connected to the toggles at their knuckle joints and adapted to move the latter in opposite directions to break the joints across a transverse 20 vertical central plane through the press box, substantially as described.

In testimony whereof I affix my signature.

JAMES M. PEERSON.
